UNITED STATES PATENT OFFICE.

EDWARD BLOUNT WINTERS, OF COFFEYVILLE, KANSAS, ASSIGNOR TO THE JOHNSON SPRING GARTER CO., OF COFFEYVILLE, KANSAS.

GARTER.

1,127,567.

Specification of Letters Patent.

Patented Feb. 9, 1915.

Application filed June 3, 1914. Serial No. 842,682.

To all whom it may concern:

Be it known that I, EDWARD B. WINTERS, a citizen of the United States, and a resident of Coffeyville, in the county of Montgomery and State of Kansas, have invented certain new and useful Improvements in Garters, of which the following is a specification.

My invention relates to garters, and is an improvement over the forms shown and described in Letters Patent of the United States, No. 1,022,217, issued to me April 2, 1912, and my applications for Letters Patent filed March 25, 1914 and May 19, 1914, Serial Nos. 827,116 and 839,523, respectively, 15 resembling the form shown in the first named application most nearly, but is distinctive therefrom by the fact that, while I still employ the inelastic bands, bifurcated shield, and yoke-spring, the spring arms are firmly secured to the shield, one end of the 20 band is permanently secured to the shield, and the other end thereof is in detachable connection with the shield, this being my present preferred form of construction.

My invention is fully described in the following specification, of which the accompanying drawing forms a part, and in which I have shown a band *a*, permanently secured at one end to the shield *b* and in detachable 30 connection, at the other end, with a loop *a*² on the shield by means of an eye *a*³ and hook *a*⁴, a sliding buckle *a*⁵ also being employed to adjust the length of the leg-band *a*.

The shield is divided into two similar 35 members *b*² and *b*³, held in normal juxtaposition by means of a spring *c* formed into a coil *c*² stitched to the shield, as shown at *b*⁴, and the ends *c*³ and *c*⁴ being upwardly directed and substantially parallel to a point 40 adjacent the top of the shield, where said ends are turned on themselves in a downward incline, as shown at *c*⁵ and *c*⁶, which portions are stitched to the corresponding shield members as shown at *b*⁵ and *b*⁶, the 45 extreme ends of said spring being turned inwardly, as shown at *c*⁷ and *c*⁸, to prevent their removal from the stitching. I also secure a dependent stocking clasp *d* to the shield and which may be of any desired

construction, many forms thereof being now 50 in use.

It will be understood that the spring arms *c*³ and *c*⁴ exert a strain toward each other, whereby the shield members will be returned to the normal position shown after having 55 been forcibly pulled therefrom, thus providing a sufficient degree of elasticity to the leg-band whereby the garter accommodates itself to knee action on the part of the wearer, and I may, if desired, inclose the 60 spring *c* within the fabric of the shield for concealment, but in its present position it is easily substituted if one should break or the elasticity thereof be lost.

My garter is adjustable, and very easy on 65 the leg; while I have shown certain preferred details, it will be obvious that these may be modified, within the scope of the following claims.

With such reservation, what I claim as 70 new, and desire to secure by Letters Patent, is:—

1. A garter, comprising a bifurcated shield, a leg band in permanent connection, at one end, therewith, means for detachably 75 connecting the other end of the band with said shield, and a spring provided with arms secured to corresponding shield members.

2. A garter, comprising a bifurcated 80 shield, a leg band in permanent connection, at one end, therewith, means for detachably connecting the other end of the band with said shield, and a spring formed into a coil secured at the fork of said shield members 85 and the ends thereof being upwardly directed and secured to corresponding shield members.

3. A garter, comprising a bifurcated shield, a leg band in permanent connection, 90 at one end, therewith, at the top of one of the shield members, means for detachably connecting the other end of the band to the upper portion of the other shield member, and a spring provided with arms arranged 95 one on each side of the slit forming said bifurcation and secured to corresponding shield members, the extreme ends of said

spring being formed to resist removal from said securing means.

4. A garter, comprising a shield provided with a pair of members separated by a slot, 5 a spring mounted upon said shield and provided with extending portions secured to said members, and a leg band connected with said members.

Copies of this patent may be obtained for five cents each, by addressing the "Commissioner of Patents, Washington, D. C."

In testimony whereof I have signed my name to this specification in the presence of 10 the subscribing witnesses.

EDWARD BLOUNT WINTERS.
